(57) **CLAIM**

The ornamental design for a vibrating massage device, as shown and described.

DESCRIPTION

FIG. 1 is a front elevational view of a vibrating massage device showing my new design;

FIG. 2 is a rear elevation view thereof;

FIG. 3 is a right side elevational view thereof;

FIG. 4 is a bottom elevational view thereof;

FIG. 5 is a left side elevational view thereof;

FIG. 6 is a top elevational view thereof;

FIG. 7 is a left bottom perspective view thereof; and,

FIG. 8 is a right top perspective view thereof.
